No. 723,705.

PATENTED MAR. 24, 1903.

C. NUNAN.

GRATE.

APPLICATION FILED MAY 21, 1902.

NO MODEL.

THE NORRIS PETERS CO., PHOTO-LITHO., WASHINGTON, D. C.

UNITED STATES PATENT OFFICE.

CLARA NUNAN, OF CAPE PORPOISE, MAINE.

GRATE.

SPECIFICATION forming part of Letters Patent No. 723,705, dated March 24, 1903.

Application filed May 21, 1902. Serial No. 108,398. (No model.)

To all whom it may concern:

Be it known that I, CLARA NUNAN, a citizen of the United States, residing at Cape Porpoise, in the county of York and State of Maine, have invented new and useful Improvements in Grates, of which the following is a specification.

My invention relates to new and useful improvements in grates; and its object is to employ a device of this character having a movable section whereby apertures may be formed within the grate of sufficient size to permit cinders and clinkers to be readily expelled therethrough and into the ash-pan.

Another object is to so construct the grate as to permit the entire device to be shaken.

With the above and other objects in view the invention consists in the novel construction and combination of parts hereinafter described and claimed, and illustrated in the accompanying drawings, showing the preferred form of my invention, and in which—

Figure 1 is a perspective view showing half of the grate in position within a stove. Fig. 2 is a plan view showing the grate in position within its supporting-frame. Fig. 3 is a section on line 3-3, Fig. 2. Fig. 4 is a perspective view of the body of the grate detached. Fig. 5 is a similar view of the sliding section of said grate. Fig. 6 is a perspective view of a tool for operating said sliding section. Fig. 7 is a detail view of the supporting-frame of the grate.

Referring to the figures by numerals of reference, 1 is a preferably rectangular supporting-frame adapted to be secured within a stove in any suitable manner and having the front thereof cut away, as shown in Fig. 7, the inwardly-turned ends 2 of said section being provided with horizontal recesses 3 for the reception of the reduced ends 4 of a horizontal strip 5. This strip is secured to or formed with the forward ends of arms 6, extending from a rectangular grate-section 7, having pairs of parallel bars 8 extending from front to rear thereof. Short arms or lugs 9 extend horizontally from the rear ends of the section 7 and project into and are adapted to slide within slots 10, formed with-

in the back of the supporting-frame 1. Op-

ositely-arranged brackets 11 are secured to the end pairs 8 of section 7 and overlap horizontally-arranged bars 12, formed within the main grate-body 13. These bars 12 are arranged in parallel series and are so located as to lie above the spaces formed between the pairs 8 of the movable section 7. The brackets 11 serve to prevent longitudinal movement of the sections of the grate independently of each other. Arms 14 extend from opposite ends of the body 13 and rest within grooves 15, formed within the upper faces of the ends of supporting-frame 1. One of these arms extends beyond the edge of frame 1 and terminates in an upwardly-bent hook 16, to which access may be obtained through a door in the stove or in any other suitable manner. As the body 13 is shorter than the internal length of frame 1, a slight longitudinal movement of said body within the frame is permitted.

An arm 17 extends forward from the movable section 7 and its cross-strip 5 and also terminates in an upwardly-bent hook 18. This hook is adapted to be engaged by parallel ears 19, formed at one end of a tool 20, and by means of this tool the arm 17, cross-strip 5, and sliding section 7 may be drawn forward until the brackets 11 contact with the front portion of body 13. Apertures will then be formed between the series of bars 12 and the rear ends of body 13 and sliding section 7, and through these apertures clinkers or other large objects upon the grate may be shoved by means of a poker or other suitable device. After the parts have been returned to normal position the ashes upon the grate may be shaken downward by placing the tool 20 in engagement with the end hook 16. The body 13 may then be moved back and forth from end to end, and as it cannot be moved independently of the movable section 7 said section will also be carried therewith. As the reduced ends 4 of cross-strip 5 are shorter than the recesses 3 within the ends 2 and as the width of lugs 9 is less than that of the slots 10, there will be nothing to hinder this reciprocating motion of the movable section 7.

It will be seen that the device is extremely

simple in construction and can be readily operated and the parts can be quickly assembled or taken apart, as desired.

In the foregoing description I have shown 5 the preferred form of my invention; but I do not limit myself thereto as I am aware that modifications may be made therein without departing from the spirit or sacrificing any of the advantages thereof, and I therefore reserve the right to make all such changes as fairly fall within the scope of my invention.

Having thus fully described the invention, what is claimed as new is—

1. The combination with a supporting-frame open at the front, of a cross - strip loosely mounted in the open front portion of the said frame, a grate-section connected to said cross-strip and having lugs loosely engaging the back of the frame and provided 15 with grate bars, a grate-body supported upon the frame and movable longitudinally thereon and having a series of grate-bars therein arranged above the spaces between the bars

of the grate-section connected to the cross-strip, and brackets on the latter section engaging the bars of the grate-body. 25

2. The combination with the supporting-frame having an opening in the front thereof, of a cross-strip loosely mounted within said opening, a grate-section connected to said cross-strip and having lugs loosely engaging the back part of the frame and also provided with bars, a grate-body mounted upon the said section and having oppositely-extending arms engaging the frame, brackets secured 30 to said section and engaging the bars of the body, and means for moving the said grate-sections transversely of the body, the latter being also movable.

In testimony whereof I affix my signature 40 in presence of two witnesses.

CLARA NUNAN.

Witnesses:

GEO. R. SMITH,
NATHAN DANE.
